UNITED STATES PATENT OFFICE.

JAMES L. CRANE, OF CLEVELAND, OHIO.

STORE-FRONT AND SHOW-CASE.

SPECIFICATION forming part of Letters Patent No. 624,460, dated May 9, 1899.

Application filed January 10, 1898. Serial No. 666,204. (No model.)

To all whom it may concern:

Be it known that I, JAMES L. CRANE, of Cleveland, Cuyahoga county, Ohio, have invented certain new and useful Improvements 5 in Store-Fronts and Show-Cases; and I do hereby declare the following to be a full, clear, and exact description of the invention, such as will enable others skilled in the art to which it pertains to make and use the same.

10 My invention relates to improvements in store-fronts or show-windows and show-cases.

The object of my invention is to provide an improved construction and arrangement of parts in fastening two glass plates that are arranged at an angle to each other at the corner formed between the said plates without weakening the said plates at their meeting or adjacent edges and without interfering with a tight fit between the plates and without 20 sealing the finely-finished edges of the plates.

With this object in view the invention consists in certain features of construction and combinations of parts hereinafter described, and pointed out in the claims.

25 In the accompanying drawings, Figure I is an exterior view of a show-front embodying my invention. Fig. II is a horizontal section on either one of lines II II, Fig. I, and shows the parts full size. Fig. III corresponds with 30 Fig. II except that in Fig. III the corner-clamp is removed. Fig. IV is a horizontal section on any one of lines IV IV, Fig. I. Fig. V is a vertical section on line V V, Fig. III, looking in the direction of the arrow. Fig. VI is 35 a view in perspective of the corner-clamp. Fig. VII is a top plan in horizontal section, corresponding in the main with Fig. II, but showing a slight modification.

Referring to the drawings, A and B designate 40 two upright glass plates of a show-window, that are arranged at an angle to each other and are tightly fitted together. The meeting or adjacent edges of the said plates are ground and polished. In the case illustrated, A represents the front plate of a show-window, and B one of the side plates of the window. In any case, however, my invention essentially involves two glass plates arranged at an angle to each other and tightly fitted 45 together. In the case illustrated the front plate A overlaps the edge of the side plate B.

To prevent the glass plates from being

broken by lateral pressure occasioned by heavy winds or by the tools or instruments employed in cleaning the plates or accidentally by persons or objects participating in the display of goods within the show-window, I provide corner clamps or fasteners D at two or more points between the upper and lower ends of the plates. Each of the said corner-fasteners involves, essentially, an outer angle-plate or jaw D', an inner jaw or plate D², means instrumental in connecting the two plates D' and D² together, and registering recesses F in the meeting or adjacent edges of the glass plates for accommodating the location and operation of the aforesaid connection. The outer jaw or angle-plate D' has two arms or wings d and d', arranged to engage the outer side of the different glass plates A and B, respectively, at the external corner formed between the two glass plates. The inner jaw or plate D² has two arms or wings d² and d³, arranged to engage the inner side of the different glass plates, respectively, at the internal corner formed between the glass plates. In the case illustrated the connection between the two jaws or plates D' D² is a stud or screw d⁴, that is rigid with the outer jaw or plate D' at the latter's angle and projects inwardly 80 in a horizontal plane and diagonally and extends through the registering recesses F F, formed in the meeting edges or ends of the glass plates, and loosely through a hole formed in the inner jaw or plate D², and a nut D⁵, 85 mounted upon the stud or screw, is arranged to secure the two jaws or plates D' D² in their operative position, wherein they clamp the two glass plates between them.

As already indicated, the two glass plates 90 A and B are ground and polished at their meeting or adjacent edges and are tightly fitted together. The sectional views Figs. II, III, and IV show the fit desired between the two glass plates. There is no drilling of holes 95 in the glass plates near the latter's edges; but the plates are recessed horizontally, as at F, in their meeting edges or ends, and the recesses F are open, therefore, at the edges of the plates and do not weaken the latter in 100 any respect. Each recess F in plate B is formed at the junction of the inner side and edge of the plate and registers with the recess F, formed in plate A, as shown more

clearly in Figs. III and V. The sectional view Fig. VII shows a slight modification, in that the front plate A projects edgewise a short distance beyond the outer side of the side plate B, so as to form an angular recess G between the outer side of the side plate and the rear side of the front plate, and in this case the arm d' of the outer angle-piece or jaw D' is enlarged inwardly, as at D³, into the said recess to form an adequate bearing for the outer side of the side plate B and to form a shoulder or bearing D⁴ for the rear or inner side of the projecting portion of the front plate A.

15. What I claim is—

1. The combination of two glass plates arranged at an angle to each other and tightly fitted together, and having registering recesses in their meeting ends, an outer angle-piece D' arranged to bear against the outer sides of the said plates; an inner piece D² arranged to bear against the inner sides of the said plates, and a connection, between the said parts D' and D², extending through the aforesaid recesses.

2. In a show-window, the combination with an upright front plate A having the recess F in its edge, and the side plate B fitting against the rear side of the front plate at the aforesaid edge, and having a recess F formed at the junction of its forward edge and inner side and registering with the recess in the front plate; an angle-piece arranged to conceal the recess in the front plate from the exterior and to bear against the outer sides of the two plates; an inner plate or piece arranged to bear against the inner sides of the said plates opposite the external angle-piece,

and a connection, between the said bearing-pieces, extending through the aforesaid recesses, substantially as and for the purpose set forth.

3. The combination of two glass plates arranged at an angle to each other, and one of them overlapping and projecting a short distance beyond the adjacent edge of the other, and both plates being tightly fitted together and having registering recesses in their adjacent edges; an outer angle-plate D' arranged to bear against the outer sides of the said plates and enlarged inwardly, as at D³, into the angular space formed between the two plates by the projection of the one plate beyond the edge of the other plate, an inner plate or piece D² arranged to bear against the inner sides of the said plates, and a connection, between the said plates, extending through the aforesaid recesses.

4. A show-window comprising two upright glass plates arranged at an angle to each other and tightly fitted together, and having, in their meeting or adjacent edges and at different points arranged a suitable distance apart vertically, registering recesses F F, and a corner-fastener at each pair of registering recesses, which fastener has a member extending through the said recesses, substantially as shown, for the purpose specified.

In testimony whereof I sign this specification, in the presence of two witnesses, this 23d day of December, 1897.

JAMES L. CRANE.
